UNITED STATES PATENT OFFICE

ORIE L. BEARDSLEY, OF GARY, INDIANA

COUPLING FOR SEPARABLE MEMBERS

Application filed March 29, 1928. Serial No. 265,688.

(GRANTED UNDER THE ACT OF MARCH 3, 1883, AS AMENDED APRIL 30, 1928; 370 O. G. 757)

The invention described herein, if patented may be manufactured and used by or for the Government for governmental purposes without the payment to me of any royalty 5 thereon.

The subject of this invention is a coupling for separable members and is especially applicable for the trails of gun carriages.

In infantry accompanying and in mountain guns which must be capable of being readily knocked down to provide individual loads for transportation the trail is of such a great weight and length that it is divided.

The principal object of the present invention is to provide a simple, effective and quickly operable coupling whereby the two sections of the trail may be connected and disconnected.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, 30 wherein:

Fig. 1 is a view in side elevation of a gun carriage whose trail is provided with the improved coupling;

Fig. 2 is a plan view, partly in section, of 35 the coupling;

Fig. 3 is a vertical sectional view of the coupling;

Fig. 4 is a detail view partly in side elevation and partly in section of the connection 40 between the two portions of the trail.

Fig. 5 is an enlarged view in side elevation of a portion of one of the trail sections.

Referring to the drawings by numerals of reference:

45 There is shown a gun carriage comprising wheels 5 and an axle 6 and a trail 7 which is divided intermediate its length to form the axle section 8 and the spade section 9. Each section is formed of spaced parallel rails 10 rigidly connected by transoms 11. In the

adjoining ends of each of the rails 10 is secured a frame, the forward frames 12 provided with a pair of apertured ears 13 and the rear frame 14 provided with a single apertured ear 15 having an elevated lateral projection 16 designed to rest on one of the ears 13 to facilitate alinement of the ears and for an additional purpose which will hereinafter appear. 55

Secured to the transom 11 of the axle section 8 is a housing 17 having cylindrical portions 18 in alinement with the ears 13. In these cylinders are disposed hinge pins 19 interconnected by a system of bars 20, 21, and 22 which constitute a double toggle joint. 60 The intermediate actuating bar 21 is centrally pivoted in the housing 17 and is provided with an upstanding apertured lug 23 through which a tool may be placed to rotate the bar 21 and by extending or flexing the toggle arrangement insert or retract the pins 19 from the apertured ears 13 and 15. 65

In order to provide rigidity to the joint which is established between the two sections of the trails one set of the frames, in this instance the forward frames 12, are formed with a projecting finger 24 having a ball end 25 which when the sections of the trail are coupled enters into socket 26 on the floor plate of the frame 14. 70 75

The operation of coupling the sections of the trails is carried out by elevating their adjoining ends above the normal coupled position, as shown in Fig. 1, to provide sufficient relative inclination which will permit the introduction of the ball end of the finger 24 into the socket 26. When this is accomplished the adjoining ends are lowered until the lateral projection 16 on the ear 15 comes into engagement with one of the ears 13 thereby preventing relative lowering movement of the spade section of the trail with respect to the axle section and by virtue of the constraint of the ball and socket connection which is maintained as a consequence 80 85 90 of the action of the projection 16 the connection thus far used will be rigid as regards lowering and the operators who have been handling the trail sections may release their hold. The projection 16 by reason of its 100

curvature 27 conforming to the ear 13 will arrest the lowering movement at a point which insures the alinement of the apertures in the ears 13 and 15.

5. In uncoupling, the pins 19 are retracted and the adjoining ends of the trail sections are raised until the finger 24 may be withdrawn from the socket 26.

I claim:

10. 1. A gun trail comprising rigidly spaced rail members divided intermediate their length to form two sections, a knuckle joint between the adjoining ends of each of the rail members of the sections, a double toggle mechanism carried by one of the rail sections for inserting and retracting the pivot pins of the knuckle joints and a ball and socket connection established between the adjoining ends of the rail members upon bringing the rail members together in a position other than the ultimate position of these members.

15. 2. A gun trail comprising rigidly spaced rail members divided intermediate their length to form two sections, a knuckle joint between the adjoining ends of each of the rail members of the sections, a double toggle mechanism carried by one of the trail sections for inserting and retracting the pivot pins of the knuckle joints and means for rendering the knuckle joint inflexible, said means brought into play upon bringing the rail members together end to end.

20. 3. In a coupling, a pair of members having ears of a knuckle joint on their adjoining ends, a disengageable pivot pin for said knuckle joint, a connection established between the adjoining ends of the members upon bringing said members together before the pin is inserted for rendering the knuckle joint inflexible and cooperating means on the ears of said members for assisting the connection in holding the members semi-rigidly in a plane perpendicular to the pivot pin before the pivot pin is inserted.

25. 4. In a coupling, a pair of members having elements of a knuckle joint on their adjoining ends, a disengageable pivot for said knuckle joint and a ball and socket connection established between the adjoining ends of the members upon bringing said member together for rendering the knuckle joint inflexible.

30. 5. In a coupling, a pair of members having interfitting elements of a knuckle joint on their adjoining ends, a disengageable pivot pin insertable through the interfitting elements, and means immovably carried by the adjoining ends of the members and cooperating to immobilize the joint, said means brought into operative position in the act of bringing the members together end to end.

35. 6. In a coupling, a pair of members having interfitting elements of a knuckle joint on their adjoining ends, a disengageable pivot pin insertable through the interfitting ele-

ments, and means immovably carried by the adjoining ends of the members and cooperating when the members are assembled to immobilize the joint.

7. In a coupling, a pair of members having interfitting elements of a knuckle joint on their ends, a disengageable pivot insertable through the interfitting elements and means on the interfitting element of one member engageable with the interfitting element of an other member for facilitating alinement of said elements.

8. A gun trail comprising rigidly spaced rail members divided intermediate their length to form two sections, a knuckle joint between the adjoining ends of each of the rail members of the sections and a double toggle mechanism carried by one of the trail sections for inserting and retracting the pivot pins of the knuckle joint.
